UNITED STATES PATENT OFFICE.

LUTHER L. KNOX, OF AVALON, PENNSYLVANIA, ASSIGNOR TO KNOX PRESSED & WELDED STEEL COMPANY, OF PITTSBURGH, PENNSYLVANIA, A CORPORATION OF PENNSYLVANIA.

WATER-COOLED DAMPER OR VALVE.

1,102,196.

Specification of Letters Patent. Patented June 30, 1914.

Application filed April 19, 1913. Serial No. 762,229.

To all whom it may concern:

Be it known that I, LUTHER L. KNOX, a citizen of the United States, and resident of Avalon, Allegheny county, Pennsylvania, have invented a new and useful Water-Cooled Damper or Valve, of which the following is a full, clear, and exact description, reference being had to the accompanying drawings, forming part of this specification, in which—

Figure 1 is a transverse section of a furnace flue having my improved damper or valve applied thereto; Fig. 2 is a longitudinal section of the same; Fig. 3 is a horizontal longitudinal section; and Figs. 4 and 5 are views similar respectively to Figs. 1 and 2, but showing a modification.

My invention has relation to water-cooled dampers or valves particularly adapted for use in furnace flues, and is designed to provide a simple and efficient damper or valve of this character.

The nature of my invention will be best understood by reference to the accompanying drawings, in which I have shown two different embodiments thereof, and which will now be described, it being premised, however, that various changes can be made in the details of construction and arrangement of the parts without departing from the spirit and scope of my invention as defined in the appended claims.

Referring first to that form of my invention shown in Figs. 1, 2 and 3, the numeral 2 designates the masonry walls of a furnace flue, and the refractory lining 3. 4 designates the water-cooled damper or valve which is of hollow rectangular form, and is designed to be kept filled with cooling water circulated therethrough. In order to form seats for the edges of the valve when in its closed position, the side walls of the flue end of the refractory lining 3 are formed with the offsets 5 and 6, these 45 two offsets being out of transverse alignment with each other to such an extent that the end wall 5^a of the offset recess 5 will form a seat for one edge portion of the valve wall, and the opposite end wall 6^a of the offset seat 6 will form a seat or abutment for the opposite edge of the valve. These offset recesses are of sufficient extent lengthwise of the flue to permit the valve to turn to an open position at right angles to the closed position, as shown in

dotted lines in Fig. 3. In order to form a sealing seat for the bottom edge of the valve, the bottom wall of the flue and lining has the cut-away portions 7 and 8, so arranged that the wall 7^a of the portion 7 is in transverse alignment with the seating wall 5^a, and the wall 8^a of the portion 8 is in transverse alignment with the seating wall 6^a. The longitudinal walls 7^b and 8^b of these cut-away portions are sufficiently out of longitudinal alignment to form opposite seating surfaces for the valve when turned to the full open position shown in dotted lines in Fig. 3. The valve is mounted to oscillate upon a vertical shaft 9, which is stepped in a suitable bearing 10 at its lower end, and which is shown as having the ball bearing 11 above the valve. This ball bearing is interposed between the upper end of an upwardly extending central sleeve 12 of a water pan 13 seated in the top wall of the flue, and the top member of an inverted cup 14. This cup member 14 is secured to a hollow sleeve 15, which surrounds the upper portion of the shaft 9 but communicates at its lower end with the interior of the valve at the top of the latter. The cup member 14 and the sleeve 12 form co-operating gas sealing members, the opening between which is sealed by the water in the pan 13. The shaft 9 is made hollow for the introduction of the cooling water, having a suitable supply connection 16 at its upper end. The water passes downwardly through this hollow shaft 9, and escapes at the lower portion of the valve into the interior thereof through the discharge arms 17. As it becomes heated it rises to the upper portion of the valve and thence passes into the sleeve 15. Connected to the upper portion of this sleeve is a discharge pipe 18, which extends downwardly into the water pan 13. The upper end of the pipe 18 has a vent arm 19 for the escape of any steam which may form. The cooling water is in this manner first introduced into the lower portion of the valve, rising therein as it becomes heated, and thence flowing into the pan 13, from which it escapes by means of a suitable overflow connection 20. The valve can be oscillated in any suitable manner, as by lever handle 21 attached to the sleeve 15. The upper edge of the valve may be sealed in a somewhat similar manner to its lower edge by means of downward projections 22 and 110

23 on the bottom of the water pan 13. These projections are arranged out of transverse alinement with each other in the manner shown in Figs. 1 and 2. The water pan provides means for the retention of a considerable body of water therein above the damper or valve; and the construction and arrangement of the top bearing in connection with this water pan is such as to form an efficient seal against the escape of any hot air or gases from the flue by passing upwardly around the sleeve 15.

Figs. 4 and 5 show a simpler form of my invention, in which the valve or damper 4^a is of similar form to that first described, but is not provided with seating abutments at either its lateral edges or at its top and bottom. In this form the water pan 13^a is shown as seated upon the top of the flue 20 wall instead of being set therein as in the form first described. The other parts shown in this figure are similar to those first described, and are given the same reference numeral with the letter *a* added thereto.

25 The advantages of my invention will be apparent, since it provides a simple and efficient form of water-cooled damper or valve, in which provision is made for the presence therein at all times of a relatively 30 large body of cooling water; which can be readily and easily operated; which is provided with an effective seal against the escape of gases around its operating connections; and which can be readily made to 35 seal at its edges if desired.

What I claim is:—

1. The combination with a hollow water-cooled damper or valve, a hollow actuating shaft extending, and arranged to discharge 40 water into said valve, a hollow sleeve communicating with the interior of the valve and surrounding the shaft, of a water pan seated above the damper or valve and through which the shaft and sleeve extend, 45 and the sleeve having an overflow arranged to discharge into said pan, said sleeve and shaft having within the pan coöperating gas-sealing members, the opening between which is sealed by the water in the pan, 50 substantially as described.

2. The combination with a flue or discharge having its lateral walls provided with offset recesses, of a damper or valve

for controlling said flue and said valve being mounted to swing on a vertical axis and arranged to seat at its edges against opposite vertical end walls of said recesses, and the closed bottom wall of the flue having depressions, the opposite end walls of which form seating abutments for the lower portion of the valve in one position thereof, and opposite longitudinal walls which form seating abutments for the lower edge of the valve in another position thereof; substantially as described.

3. The combination with a flue or discharge having its lateral walls provided with offset recesses, of a damper or valve for controlling said flue and said valve being mounted to swing on a vertical axis and arranged to seat at its edges against opposite vertical end walls of said recesses, and the closed bottom wall of the flue having depressions, the opposite end walls of which form seating abutments for the lower portion of the valve in one position thereof, and opposite longitudinal walls which form seating abutments for the lower edge of the valve in another position thereof; and the top of the flue having seating abutments for the upper edge portion of the valve; substantially as described.

4. The combination with a flue or discharge having its lateral walls provided with offset recesses, of a damper or valve for controlling said flue and arranged to seat at its edges against opposite end walls of said recesses, and the bottom wall of the flue having depressions, the opposite end walls of which form seating abutments for the lower portion of the valve in one position thereof, and opposite longitudinal walls which form seating abutments for the lower edge of the valve in another position thereof, and a water pan seated upon the top of the flue and having depending projections which form seats or abutments at the upper edge portion of the valve; substantially as described.

In testimony whereof, I have hereunto set my hand.

LUTHER L. KNOX.
